UNITED STATES PATENT OFFICE.

MORRIS KLINE, OF CHICAGO, ILLINOIS, ASSIGNOR TO THE LIGHT HOUSE RUG CO., OF CHICAGO, ILLINOIS, A CORPORATION OF ILLINOIS.

RUG.

Application filed February 15, 1924. Serial No. 692,990.

My invention relates to rugs and more particularly to a rug provided with suitable filler members.

It is a purpose of my invention to provide a rug that is made up of warp threads that form the pattern therein and weft or shuttle threads comprising large cords, ropes or filler members, such as jute twine or what is known as cotton roving, that suitably thicken the same, and further, to provide means for binding or securing said filler members in substantially fixed position in the rug, said means preferably being in the form of binding weft or shuttle threads alternating with the filler members.

It is still a further purpose of the invention to provide a rug of the above mentioned character which is strong in texture, one that will hold its shape and one that can be readily washed.

Other objects and advantages of the invention will appear as the description of the accompanying drawings proceeds. However, I desire to have it distinctly understood that I do not intend to limit myself to the exact details shown or described but that I intend to include as part of my invention all such changes or modifications of parts as would occur to a person skilled in this art and as would fall within the scope of the claims.

In the drawings:

Fig. 1 is an enlarged fragmentary plan view of a portion of my rug showing the arrangement of the warp and weft threads therein; and

Fig. 2 is an enlarged fragmentary sectional view thereof.

Referring in detail to the drawings, the rug comprises the warp threads 3 and 3', said threads being preferably of contrasting colors although this is not necessarily true. They are so indicated in the drawings, the threads 3 being indicated as being white, or substantially so, and the threads 3' as being colored by crosshatching the same in Fig. 1. Interwoven with the threads 3 and 3' are the weft or shuttle threads 4 and 5. The members 4 are in the form of filler members and may be made of any suitable material such as jute twine or cotton roving, and the threads or cords 5 may be made of any suitable material but are preferably a form of twine having considerable strength.

It will be noted that the members 5 are

woven into the material to alternate with the filler members 4 passing in and out between the members 3 and 3' on both sides of the filler members 4 to thus firmly bind the filler members 4 in position and prevent shifting of the same lengthwise of the warp threads as well as transversely thereof. In the drawings the warp threads are shown as being paired but this is, of course, not absolutely necessary as any arrangement of warp threads may be used. The use of the paired warp threads however has an advantage in the fact that the pairs of threads where they pass between the filler members and the binders are able to turn a quarter turn as shown in Fig. 1 and thus present only the thickness of a single thread lengthwise of the fillers between adjacent filler and binder members. As this is the point where the two sets of warp threads cross, the combined distance which the two sets extend lengthwise of the fillers at this crossing point is the same as that which one pair of the warp threads extends on the top and bottom of the filler threads. This makes it possible to substantially fully cover the filler members with the warp threads.

It will be noted, upon reference to Figs. 1 and 2, that the pattern in the material is obtained by varying the arrangement of the filler members relative to the binding members so that the threads 3' are thrown on the opposite side of the fabric or rug on one side of the place where the variation occurs than on the other side thereof. For example, it will be noted that slightly to the right of the center of Fig. 2 two of the filler members 4 are adjacent without the interposition of a binder member therebetween. Upon reference to Fig. 1 it will be seen that where the two members 4 are adjacent the threads 3' are on the side that is upward in Fig. 1 relative to one of the members 4 and the threads 3 are upward relative to the member 4 at the left thereof.

The method of weaving the fabric is to provide the two sets of warp threads, which are preferably of contrasting colors, and to provide the loom with two shuttles, one of which carries the thick filler member and the other of which carries a relatively fine binding member and alternately throwing the shuttles across between the warp threads so that first a binding thread is interwoven with the warp threads, then a filler is inter-

woven with the warp threads and then again a binding member is interwoven with the warp threads, and so on.

It will be obvious from the above that a very strong weave is obtained in the rug, due to the fact that the filler members are securely bound in position by the binding threads or members and that the rug will lie flat, due to the fact that the filler members are held substantially in parallelism by the binding members, that the rug can be very easily washed and, in fact, can be scrubbed without being run through a washing machine or similar device because of the close weave thereof which prevents dirt from going through the meshes of the rug and in between the threads thereof, any dirt remaining substantially on the surface of the rug which can be easily removed by merely scrubbing the surface thereof with a brush.

Having thus described my invention, what I desire to claim and secure by United States Letters Patent is:

25 1. A rug of the character described having alternating weft threads comprising enlarged filler members of cord or rope and smaller binding members alternating with said filler members, and alternating pairs of 30 warp threads interwoven with said filler and binding members, each pair of said warp

threads being twisted substantially a quarter turn between the portions overlying the filler members and the portions extending between adjacent filler and binding members whereby said warp threads substantially cover the opposite sides of said filler members.

2. A rug of the character described having alternating weft threads comprising enlarged filler members of cord or rope and smaller binding members alternating with said filler members, and alternating pairs of warp threads interwoven with said filler and binding members, each pair of said warp threads being twisted substantially a quarter turn between the portions overlying the filler members and the portions extending between adjacent filler and binding members whereby said warp threads substantially cover the opposite sides of said filler members, certain pairs of said filler members having no binding members therebetween and said warp threads shifting from one side to the opposite side of said filler members between the filler members of said certain pairs to make the pattern of the rug.

In witness whereof, I hereunto subscribe my name this 5th day of February, A. D. 1924.

MORRIS KLINE.
